UNITED STATES PATENT OFFICE.

FRANCIS J. COLE, OF SCHENECTADY, NEW YORK

LOCOMOTIVE TRAILING TRUCK.

1,311,875.

Specification of Letters Patent.

Patented Aug. 5, 1919.

Application filed May 10, 1919. Serial No. 296,075.

To all whom it may concern:

Be it known that I, FRANCIS J. COLE, of Schenectady, in the county of Schenectady and State of New York, have invented a certain new and useful Improvement in Locomotive Trailing Trucks, of which improvement the following is a specification.

The object of my invention is to provide a four wheeled trailing truck, which may be located below the fire-box of a locomotive, in proper relation thereto, to support the over-hanging weight in rear of the driving wheels, without involving any change in the general design of the fire-box, ash-pan, or accessories, as heretofore constructed, in standard practice, or any substantial detail modification of the ash pan.

The improvement claimed is hereinafter fully set forth.

- 20 In the accompanying drawings: Figure 1 is a side view, in elevation, of the rear portion of a locomotive engine, illustrating an embodiment of my invention; Fig. 2, a half plan view, with the firebox removed; Fig. 3, a vertical transverse section, on the line *a a* of Fig. 1; and, Fig. 4, a view, the left hand half of which is a rear elevation, and the right hand half, a vertical transverse section, on the line *b b* of Fig. 1.
- 30 In the practice of my invention, referring descriptively to the specific embodiment thereof which is herein exemplified, I provide a truck frame comprising two parallel side members, 1, 1; a transverse central member, 1^a, connecting the side members at or about the middle of their length; and a transverse front member, 1^b, the latter being forwardly inclined from the side members to the longitudinal central plane of the 40 truck, and having a forwardly projecting radius bar, 1^c, at its middle, socketed to receive a center pin. The transverse central member, 1^a, does not carry a swing bolster or center pin as in ordinary practice, and, 45 therefore, its middle portion is narrow, and it is widened at and adjoining its ends, as shown in Fig. 2, to provide bearings to which weight is transmitted from the main frame of the locomotive, through equalizers, 50 as hereinafter described. In the instance exemplified, the truck frame is shown as built up in connected sections, but it may, if preferred, be in the form of an integral casting, without departure from the spirit and operative principle of my invention. The radius bar, 1^c, is coupled, by a center pin, to a cross tie, 3^b, secured to the side members, 3, of the main frame of the locomotive, and to the supplemental frame members, 3^a, which extend rearwardly therefrom, above the truck 60 frame.
- 55 The truck is supported on two pairs of truck wheels, 4, which pairs of wheels are fixed on two truck axles, 4^a, journaled in axle boxes, 4^b, fitted, in the usual manner, in pedestals, 4^c, fixed to the side members of the truck frame. The weight carried by the truck frame acts upon the axle boxes through truck equalizers, 5, which bear, at their ends, on the axle boxes, and are 70 coupled to the ends of springs, 6, on which the side members of the truck frame bear.
- 65 The rear driving wheels, 7, of the locomotive, are fixed on an axle, 7^a, which is fitted in boxes in the main frame, 3, in the ordinary manner, the supported weight being transmitted to the driving boxes through springs, 8. The truck, as a whole, is equalized with the rear driving wheels by main 75 equalizers, 9, which are located above the truck frame, and parallel with the side members thereof, and are journaled, by pins, 9^b, in cylindrical transmission blocks, 10, forming parts of resistance devices for controlling the swinging movements of the 80 truck. Each of the transmission blocks is fitted to move vertically in a guide, 10^a, secured to and supported by, an outwardly projecting bracket, 10^b, on the supplemental engine frame, 3^a. The lower end of the 85 block, 10, carries a shoe, 10^c, the lower face of which is downwardly inclined, in opposite directions, and bears on a roller, 10^d, journaled, in a horizontal plane, on the transverse central member, 1^a, of the truck frame. 90 Swinging movement of the truck, in either direction is resisted by the frictional resistance between the roller and shoe, and the inclined surfaces of the latter act to return the truck to normal central position, 95 when passing from a curve to a tangent of the track.
- 95 The rear end of each of the equalizers, 9, bears on an abutment, 9^c, fixed to the adjacent supplemental engine frame, 3^a, and its 100 forward end is coupled to the upper end of a link, 9^d, the lower end of which is, in turn, coupled to one end of a supplemental equalizer, 9^e, journaled in a bearing, 9^f, on the main engine frame, and having its opposite 105 end coupled to a link, 8^b, which is connected to the rear spring hangers, 8^a, of the driving

wheel spring, 8. The application of the supplemental equalizer, 9^a, enables the length of the main equalizer to be kept within desirable limits, and facilitates its connection 5 with the driving spring.

The firebox, 11^a, of the boiler, 11, is supported on the supplemental engine frame members, 3^a, in any suitable and preferred manner, as by front and rear expansion 10 plates, 12, and the only transverse members of the truck which lie under it being the axles and the comparatively narrow central transverse member, 1^a, the space below it is 15 not substantially obstructed, and an ash pan, 13, of suitable construction may be readily applied.

The invention is readily adaptable in locomotives of the present standard constructions, in which rear overhanging weight is 20 carried on wheels which are not driving wheels, and its application does not involve any substantial obstruction or modification of the standard form and dimensions of the ash pan.

I claim as my invention and desire to secure by Letters Patent:

1. In a locomotive engine, the combination of a main frame; driving wheels journaled in bearings therein; a boiler supported 30 on the main frame and having its firebox back of the rear driving wheels; a four wheeled truck located below the firebox, and pivoted, at its front end, to the main frame, said truck having a transverse member connecting its side frame members between the 35 truck axles; and equalizing mechanism, bearing on said transverse member and adapted to transfer weight thereto from the main frame.

40 2. In a locomotive engine, the combination of a main frame; driving wheels journaled in bearings therein; a boiler supported on the main frame, and having its firebox

back of the rear driving wheels; a four wheeled truck located below the firebox, and 45 pivoted, at its front end, to the main frame, said truck having a transverse member connecting its side frame members, between the truck axles; and equalizing mechanism, adapted to transfer weight from the main 50 frame to the truck frame, in the plane of said transverse member.

3. In a locomotive engine, the combination of a main frame; driving wheels journaled in bearings therein; a boiler supported 55 on the main frame and having its firebox back of the rear driving wheels; a four wheeled truck located below the firebox, and pivoted, at its front end, to the main frame, said truck having a transverse member connecting its side frame members, between the 60 truck axles; equalizing mechanism, adapted to transfer weight from the main frame to the truck frame, in the plane of said transverse member; and a resistance device for 65 controlling the swinging movements of the truck and returning it to normal central position, the action of which is applied to the truck frame in the plane of the transverse member thereof.

70 4. In a locomotive engine trailing truck, a truck frame comprising side members having pedestals for the boxes of two truck axles; a transverse front member having a radius bar at its forward end, adapted to be 75 coupled to a locomotive main frame; and a transverse central member, located between the pedestals, and adapted to receive weight transmitted from a locomotive main frame, only at bearing points located in planes exterior to such main frame.

FRANCIS J. COLE.
